UNITED STATES PATENT OFFICE.

WILLIAM G. SCHAEFFER, OF READING, PENNSYLVANIA, ASSIGNOR TO
WILLIAM F. REMPPIS, OF READING, PENNSYLVANIA.

CUSHION-FORK FOR MOTOR-CYCLES AND OTHER VEHICLES.

No. 811,250.

Specification of Letters Patent.

Patented Jan. 30, 1906.

Application filed May 19, 1905. Serial No. 261,103.

To all whom it may concern:

Be it known that I, WILLIAM G. SCHAEFFER, a citizen of the United States, residing in the city of Reading, Berks county, Pennsylvania, have invented certain new and useful Improvements in Cushion-Forks for Motor-Cycles and other Vehicles, of which the following is a specification.

My invention relates to wheel-supporting forks for motor-cycles and other vehicles; and it consists in an improved cushion-fork construction for avoiding jars and vibrations on the handle-bar and the forward portion of the vehicle-frame.

The invention is fully described in connection with the accompanying drawings, illustrating a preferred embodiment thereof, and the novel features are specifically pointed out in the claims.

Figure 1 is a side elevation showing my improved fork and fork-stem connection. Fig. 2 is a plan view, and Fig. 3 a front view, of the same. Figs. 4 and 5 indicate a modification embodying the main features of my invention.

The fork-stem 1, which is fitted to the forward portion of the frame, as usual, is provided at its lower end, as shown, with a fork-connecting fitting 2, forming a T-shaped end with a rearwardly-extending pivot-arm 3 and a forwardly-extending cushion-arm 4. The fork comprises the usual fork sides 5 and a uniting crown portion 6, which, as shown, is specially formed and shaped for connection to the fork-stem fitting 2, as follows: The crown 6 is a U-shaped connection for the fork sides 5, arranged flatwise upon the latter with the bend 7 thereof extending forward of the points of junction with the

fork sides and its spread ends 8 forming a pivoting-jaw for connection to the pivot-arm 3 of the fork-stem end fitting 2 by means of a horizontal pivot-bolt 9, upon which the fork is adapted to swing a limited distance forward or backward. This swinging movement is controlled by a vertical spring connection between the forwardly-extending portion of the fork-stem fitting 2 and of the crown 6, the bend 7 of the latter, as shown,

being arranged to overlie the cushioning-arm 4 of the fitting 2 and being yieldingly con-

nected to the latter by means of a vertical bolt or bolts 10, upon which are strung spiral springs 11 and 12, arranged to press in opposite directions upon the pivoted fork-crown, 55 together with adjusting-nuts 13 for varying the tension of said springs and a casing-cup 14 and cap 15. The effect of said springs, as will be readily understood, is to provide for a vertical cushioning movement of the 60 connected forward portions of the fitting 2 and crown 6 about the pivot-bolt 9, which movement is, as usual, readily regulated for varying requirements to the extent of making the connection approximately rigid by 65 tightly drawing up the spring-adjusting nuts.

The preferred construction which has been thus specifically described may be modified without departing from the main features of my invention—for instance, as indicated in 70 Figs. 4 and 5, in which the crown 6^a is so shaped and arranged as to underlie the cushioning-arm of the fitting 2^a instead of overlying the latter, as in the preferred construction and which is shown with a single spring 75 connection instead of two.

What I claim is—

1. The combination with a fork-stem having a T-shaped fork-connecting end, of a fork having a U-shaped crown which is pivoted at 80 its spread ends to one arm of said T-shaped end and the bend of which overlies the other arm thereof and has a spring connection to the latter.

2. The combination with a fork-stem having a T-shaped fork-connecting end, of a fork having a U-shaped crown which is pivoted at its spread ends to one arm of said T-shaped end by means of a horizontal pivot-bolt, and the bend of which overlies the other arm 90 thereof and is yieldingly connected to the latter by means of a vertical bolt having reversely-acting springs thereon, means for adjusting the tension of said springs, and a casing, substantially as set forth. 95

In testimony whereof I affix my signature in the presence of two witnesses.

WILLIAM G. SCHAEFFER.
